COMBINED AUTOMOBILE COAT AND HAT HANGER

Albert Spielman, Queens, N. Y., assignor to Sanjo Utility Manufacturing Co., New York, N. Y., a corporation of New York

Application May 25, 1956, Serial No. 41,653

Term of patent 7 years

(Cl. D14—6)

I claim:

The ornamental design for a combined automobile coat and hat hanger, as shown.
